UNITED STATES PATENT OFFICE.

BENJAMIN HERSHY AND CHARLES A. HITCHCOCK, OF ERIE, PENNSYLVANIA, ASSIGNS OF ONE-HALF TO JOSEPH A. EGE AND BENJAMIN F. THORNTON, BOTH OF BRADFORD, PENNSYLVANIA; SAID HERSHY ASSIGNOR OF ONE-TWENTIETH TO SAID HITCHCOCK.

ORE-SEPARATOR.

SPECIFICATION forming part of Letters Patent No. 276,534, dated April 24, 1883.

Application filed December 18, 1882. (No model.)

To all whom it may concern:

Be it known that we, BENJAMIN HERSHY and CHARLES A. HITCHCOCK, citizens of the United States, residing at Erie, in the county 5 of Erie and State of Pennsylvania, have invented new and useful Improvements in Ore-Separators, of which the following is a specification.

The object of our invention is to provide a 10 novel and efficient machine for separating ore in such manner that the gangue will be so acted upon that it is stratified, the particles arranging themselves according to their specific gravities, whereby the heavier and more valuable particles form the lower strata. This 15 we accomplish by the mechanism illustrated in the accompanying drawings, in which—

Figure 1 represents a side elevation of an apparatus constructed in accordance with our 20 invention; Fig. 2, an end elevation of the same; Fig. 3, a top or plan view of a copper frame-work designed to be used on one of the troughs; Fig. 4, a section taken transversely through the amalgamating-trough and its inner copper trough and copper frame; Fig. 5, a 25 section taken transversely through the separating-trough and its inner copper amalgamating-trough; Fig. 6, an enlarged view of a portion of one of the troughs, with the devices for separating the lighter from the heavier 30 strata of material.

The frame of this apparatus consists of the bottom pieces, A, upon which the side sills, B, rest. Inclined posts or side pieces, B', are secured to and rise from the sills, and are connected at their upper ends with the bars or stringers C. The frame also includes vertical end posts, B'', which support the ends of the stringers, and cross-bars D, which connect the 35 upper end portions of the frame. It will be understood, however, that any other suitable arrangement of bars and braces can be employed, so as to form a strong, substantial frame, in which supports and bearings are provided for the several operative parts of the apparatus.

E and E' respectively indicate separating-troughs, which can be made of any desired

length and width, and which are suspended, one above the other, the one, E, by means of links a, and the one, E', by links a and suitable rollers, a'. These troughs are preferably made of wood, for the sake of lightness, and each is open at one end, so as to admit of the free discharge of the material. The trough E may be provided with an amalgamating-trough, e, which is located in the bottom thereof, and is used for holding any free gold that may be present in connection with sulphurets, and which it is desirable to save. If requisite, each trough can be provided with a copper trough for the purpose stated. These troughs are given a reciprocating movement or longitudinal shake by means of the pitmen e', connecting with the troughs at one end by the pins fastening the lower ends of links a, and at the opposite ends connecting with the double cranks d. These crank-shafts have their bearings in the vertical end posts, B'', and are provided at one end with the bevel-gears F, which mesh with bevel-gears F' upon a vertical shaft F², which is supported at its lower end in a suitable step, f, at the base of the machine. The upper end of said vertical rotary shaft passes through a bearing in an extension of one of the cross-bars D, and is provided with a belt-pulley, f'. The lower crank-shaft d is provided on one of its ends with a pulley, G, for a belt, which will be hereinafter referred to.

K, Figs. 1 and 6, indicates a thin knife-edged plate extending horizontally at the discharge end of each one of the separating-troughs, and set at such distances above the bottom of the trough that any proportional amount of the material treated in the trough, and which it is desired to save, will, while the material passes to the discharge end of the trough, pass under said plate, and be directed by the latter into the receiving end of the trough below, while the remaining upper portion of the mass treated will pass over said plate as tailings and be conducted off by the chute H, which latter can be simply a downwardly-inclined extension of the plate K.

As it is practically impossible at one opera-

tion to make an entire and clean separation of the gold from the sand or dirt with which it is mingled without the intervention and use of mercury, and as the danger of loss of mercury is very great where large quantities of gangue are rapidly handled, the devices hereinbefore described are designed for the rapid concentration of the large quantities of material which is not rich in gold. These devices are supplemented by the following means, which are adapted for the more elaborate and safe handling of the portions which have been enriched by previous operations.

L indicates a wooden trough, which is similar in construction to the trough E. This trough, at one of its ends, is suspended by links a, pivoted to the frame of the machine, and at its opposite end supported on rollers O'. These rollers are pivoted to uprights b, which also provide bearings for a shaft, L', carrying a drum or cylinder, M, or having an enlarged cylindrical portion which is provided with a peripheral series of horizontal blades or wings, m, so as to constitute a rotary elevator. One end of the shaft L' extends through a casing, m', in which the said rotary blade-cylinder is located, and is provided with a pulley, W, driven by a belt, g², from the pulley G, as shown in Fig. 1. The shield or casing m', which partially surrounds this rotary elevator, has a chute, m², for discharging the tailings. The trough L is provided with an inner copper trough, g, extending from end to end thereof, and bent up at one end, as indicated at g'.

As it is important that the several troughs should be so hung as to be capable of an independent adjustment, so as to be suspended at different degrees of inclination, each one of the bell-crank levers L² is pivoted at its middle, and at its upper end is provided with a slot, L³, through which a bolt or set-screw passes and is secured on the frame of the machine. By such means the levers can be turned about their pivots, so as to raise or lower their lower arms, and then secured in position by means of the set-screws. The trough E' is made curved at or near its middle portion, as at e², and on each side of said curve it is made straight and inclined downwardly to its ends.

S indicates a net or frame, made of copper wires or strips s, said frame being adapted to lie in one of the troughs, in the present example it being located in the trough L, as shown in Fig. 4; but, if desired, one of such copper frames can be located in each of the troughs.

T indicates a hopper, which is arranged for feeding the material into the upper trough, E.

It will be observed that the links supporting the trough E are hung upon the lower ends of the bell-crank levers, so as to incline toward one end of the machine, and that the upper or highest end of the trough is at such end of the apparatus, the open or discharge end of the trough E being higher than the other end, over which latter end the hopper is located. The length of these links between their respective pivots should so far exceed

the length of stroke of the crank operating the pitman connected with the said trough that while the crank makes a complete revolution the lower end of each link will describe only a limited arc of a circle; also, the links are pivotally connected to the bell-crank levers in such manner that on the back-stroke of the pitman they will still be in an inclined position, whereby on the forward stroke of the pitman the trough will rapidly rise into the higher position, as indicated by dotted lines y, Fig. 1.

The operation is as follows: Shaft F² being rotated, motion will be transmitted to the crank-shafts d through the medium of the bevel-gears, and hence the pitmen connecting the crank portions of said shafts with the troughs will impart a reciprocating motion to the latter. The material to be treated is by any suitable means fed into one end of the upper trough, and owing to the reciprocating motion of the latter the material will be carried forward and upward to the discharge end of the trough. This forward and upward feed of the material is attained by reason of the manner of suspending the trough, since while the trough, in its forward and upward motion, will carry with it the material, the sudden return or backward and downward movement of the trough, caused by the arrangement of links and revolution of the crank-shaft, will cause a momentary suspension of the contents of the trough, the said contents then falling or resting on the bottom of the trough at an advanced point, corresponding with the stroke of the crank, the length and inclination of the links, and the speed at which the crank revolves.

It may here be observed that a little practice will enable the operator to adjust the bell-crank and links for the proper treatment of any particular kind of material to be treated.

During the above operation one very important result is attained—namely, the stratification of the material. This results as the effect of separate but simultaneously-operating cranks: First, the motion of the trough will cause such a shifting of the particles that the heavier ones will gravitate to the bottom of the trough, and, secondly, when the bottom of the trough, in its downward and backward movement, momentarily leaves or shifts away from the mass, which is substantially in suspension, there is a tendency to create a vacuum between the bottom of the trough and its contents.

The plates or blades K for separating the material into two layers are arranged in the troughs E E', as low as consistent with the saving of the valuable portion of the mass, which latter will pass under the plates or blades, while the tailings or less valuable portions, owing to their lightness, form the upper strata and pass over the plates or blades to the discharge-spouts H. In order to conduct the lower strata from one trough to another to secure further separation of the same, we provide a depending inclined plate, K', which is

connected with or adjacent to the outer edge of the horizontal plate K of each trough, in such manner that the lower strata in the upper trough, E, will be retarded in its outward passage from the said trough and deflected directly downward to the receiving end of the trough E', while the lower strata in the trough E will be deflected in a like manner into the trough beneath it, which, as here shown, is 10 the amalgamating-trough L. It will thus be seen that the mass is not only stratified, but the more valuable portion—that is, the lower strata—is directed from one trough to another for further separation, while the tailings pass 15 over the horizontal plates or blades into the discharge-spouts.

When it is desired to employ mercury for immediate amalgamation the trough L is brought into use. The object of this trough 20 is to provide an amalgamating device which can be silvered or amalgamated, to furnish a receptacle within which an excess of mercury can be safely used without danger of loss of either the mercury or the amalgam, and to 25 serve, in connection with its operating mechanism, for a slow, safe, and certain handling and treatment of the material, so that the entire mass shall be stratified, as in the first-described process, whereby the gold shall come into such 30 direct and continued contact with the mercury that every particle of the mass which may be in a fit condition for combining with mercury will remain below the discharging-line of the trough, while the remainder or refuse will be 35 thrown out by the rotary elevator. Any other heavy and valuable material—such as coated gold and sulphurets, which do not combine with quicksilver—are also retained in the trough until they shall, by reason of their accumulation, 40 reach the discharging-line of the trough. The copper-frame (shown in Fig. 3) is also to be silvered, and is designed to furnish additional amalgamating-surface for the free gold. This net or frame-work, which can, however, 45 be omitted, if desired, serves, by reason of its cross-rods, as riffles for the retention of materials of value, its upper surfaces constituting bearings for the lighter contents of the trough as they are by the motion of the trough carried 50 to the discharging end thereof. It is desirable to remove the material from the discharging end of the trough with as little disturbance to the lower contents of the trough as possible. To such end the blades of the rotary blade-cylinder, 55 constituting the elevator hereinbefore referred to, raise the upper portion of the material through the casing surrounding the blade-cylinder, and discharge the material into the spout leading from said casing. The blade-cylinder will be so set that the outer edge of 60 the blades will dip as deep in the trough as may be required to remove a portion of its contents, the blades raising such material as comes within their reach. The remaining portions 65 of the material in the trough are to be treated or removed, as required.

We do not here claim the construction and

arrangement of trough and its concomitants for amalgamating by the use of mercury, as such will constitute the subject-matter of a separate 70 application for Letters Patent.

We are aware that ore-separators have heretofore been provided with reciprocating trays or troughs located one above the other, the material being treated passing successively 75 from one tray to the other; also, that the tailings from quartz-mills have heretofore been run through a stationary water-sluice having at its discharge end a tail-blade for dividing the running current horizontally, cutting off 80 the lowest stratum of coarse sand containing fine sulphurets, and discharging the same into a reservoir, after which the fine sulphurets are separated from the coarse sand by passing them through a sieve. Such features do not 85 constitute our invention, and are not claimed by us; but,

Having thus described our invention, what we claim is—

1. A trough for separating ore, having its 90 end where the material is discharged arranged in a plane above its end where the material is received, and such elevated discharge end provided with a plate or blade for separating the ore into two layers, combined with mechanism 95 for supporting, reciprocating, raising, and lowering the trough, whereby the ore is stratified, substantially as described.

2. The combination, in an ore-separator, of a series of troughs located one above the other, 100 and the upper trough provided with a plate or blade at its discharge end to separate the mass being treated into two layers, with means for deflecting that layer which passes under the separating-plate into the trough below for 105 further separation, and means for carrying off that layer which passes over the separating-plate, substantially as described.

3. The combination, in an ore-separator, of a series of troughs supported one above the 110 other, with their ends where the material is discharged arranged in a plane above their ends where the material is received, mechanism for reciprocating the troughs, a plate secured at the discharging end of the upper trough 115 for separating the material into two layers, means for directing the layer which passes under the separating-plate into the trough below for further separation, and a discharge-chute for carrying off the layer which passes 120 over the plate, substantially as described.

4. The combination, in an ore-separator, of a series of troughs arranged one above the other, mechanism for vibrating the same, a plate secured at the discharging end of the upper 125 trough for separating the material into two layers, and a depending plate at the outer end of the separating-plate for deflecting the layer passing under the latter into the trough below for further separation, substantially as described.

5. The combination, in an ore-separator, of a series of troughs arranged one above the other, mechanism for reciprocating the same,

a plate secured to the discharge end of the upper trough for separating the material into two layers, a depending plate located at the outer end of the separating-plate for deflecting the layer passing under the latter into the trough below for further separation, and a discharge-chute for conveying off the layer passing over the separating-plate, substantially as described.

10 6. The combination, with the separating-trough, of bell-crank levers L^2 , pivoted at their angles, the links a , pivoted to one arm of such levers and to the trough, and means whereby the other arm of the levers can be adjusted and held, substantially as and for the purpose described.

15 7. The combination, with a series of sepa-

rating-troughs arranged one above the other, of posts at the sides of the troughs, the bell-crank levers pivoted at their angles to the 20 posts, the links pivoted to one arm of the levers and to the troughs, and means whereby the other arm of the levers may be adjusted and held, substantially as and for the purpose described.

25

In testimony whereof we have hereunto set our hands in the presence of two subscribing witnesses.
